UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,139,060.

Specification of Letters Patent. Patented May 11, 1915.

Application filed June 12, 1914. Serial No. 844,816.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft-rigging for railway cars.

The object of my invention is to provide a draft-rigging of simple construction and efficient operation.

In the drawings forming a part of this specification, Figure 1 is a side elevation of partly vertical longitudinal section of a draft-rigging embodying my invention and illustrative of the parts in their normal position. Fig. 2 is a horizontal section on line 2—2 of Fig. 1 but showing the position of the parts upon partial compression of the 25 compression resisting elements in buffering movement of the draft-rigging. Fig. 3 is a cross section taken on line 3—3, Fig. 1. Fig. 4 is a horizontal section showing the 30 position of the parts in full buff. Fig. 5 is a perspective view of one of the followers and Fig. 6 is a perspective view of one of the spring caps.

Referring to the drawings, the numerals 7—7 indicate draft members or parts of the 35 car frame to which the draft-rigging is applied. Stop members 8—8 are secured to the draft members preferably by rivets 9—9, each stop member being provided with the front stop shoulders 10—10, front limiting stop shoulders 11—11, rear limiting stop shoulders 12—12 and rear stop shoulders 13—13. Said stop shoulders are also each provided with front spring stop shoulders 14—14, front intermediate spring stop 40 shoulders 15—15, rear intermediate spring stop shoulders 16—16 and rear spring stop shoulders 17—17. A draw-bar 18 (only rear end thereof being shown in the drawings), is mounted between the draft members, the same having secured thereto a draft yoke 19. Mounted within the yoke 45 are the front and rear followers 20 and 21 respectively. Each of said followers being preferably hollow having a transverse slot 50 therethrough. In preferable construction, the front wall 23 of each of said followers and the rear wall 24 of each of said followers is convex. Through the transverse opening in each follower is passed a flat spring member 25, each of said members comprising preferably a plurality of flat spring plates 26—26 which are straight in their normal position as illustrated in Fig. 2 of the drawings. The spring members 25 extend at either end beyond the 55 follower and are each provided at their ends with a spring cap 27, which spring cap preferably consists of a substantially rectangular member having an inwardly opening recess 28 to receive an end of the 60 flat spring member. The front and rear walls 29 and 30 respectively forming the recess 28, are perforated to receive a pin or key 31 which passes through registering perforations 32 in the spring plates and is 65 adapted to hold the spring cap in engagement with the flat springs. A resilient member 33 is mounted between the followers of said member, preferably comprising an outer spring 34 and an inner spring 35 70 nested therein, the said springs being seated at their ends against the followers, each of said followers being provided in preferable construction with an intermediate 75 boss 36 about which the ends of the inner 80 spring 35 are seated. A tie-plate 37 is secured to the draft members by suitable means, preferably the bolts 38—38, the same being adapted to hold the gear in position 85 between the draft members. On rearward movement of the draw-bar, the rear follower is stopped against rearward movement through the engagement of this spring cap against the rear spring stops shoulders 17—17. The front follower moves rearwardly compressing the springs between the followers until the spring caps of the front follower engage the intermediate spring stop shoulders 15—15. Prior to this engagement the flat springs of the rear follower will be under tension and following such engagement the further rearward movement of the draw-bar will be also resisted by the flexing flat springs of both the front and rear followers until the front 100 followers engage the front limiting stop shoulders 11—11 and the rear follower engages the rear stop shoulders 18—18.

The relative position of the parts when under compression in full buff, is illustrated by Fig. 4 of drawings. On forward movement of the draw-bar the parts of the draft gear are forwardly compressed by the movement of the draft yoke, the action of the parts on forward movement being similar to that hereinbefore described.

I claim:

- 10 1. In a draft-rigging for railway cars, followers, springs extending from the ends thereof and spring caps inclosing the ends of said springs.
- 15 2. In a draft-rigging for railway cars, a follower, having a transverse recess, springs within said recess, spring caps at the ends of said springs and means for connecting said spring caps to the springs.
- 20 3. In a draft-rigging for railway cars, a follower, flat springs in engagement therewith, spring caps inclosing the ends of said

springs and pins or keys securing said caps to the springs.

4. In a draft rigging for railway cars, a follower, flat springs extending transversely of said follower and in engagement therewith, and spring caps secured to the ends of said springs, said caps being movable relatively to said follower.

5. In a draft rigging for railway cars, a follower having a transversely extending recess therethrough, flat springs extending through said recess and beyond the edges of the follower, spring caps secured to the ends of said springs, said caps being substantially channel shape in cross section, the caps being movable back and forth relatively to the follower.

JOHN F. O'CONNOR.
